US00D897149S

(12) **United States Design Patent** (10) **Patent No.:** **US D897,149 S**
Sorensen et al. (45) **Date of Patent:** **** Sep. 29, 2020**

(54) **LID FOR A CONTAINER**(71) Applicant: **RUNWAY BLUE, LLC**, Alpine, UT (US)(72) Inventors: **Steven M. Sorensen**, Alpine, UT (US); **David O. Meyers**, East Layton, UT (US)(73) Assignee: **Runway Blue, LLC**, Alpine, UT (US)(***) Term: **15 Years**(21) Appl. No.: **29/650,949**(22) Filed: **Jun. 11, 2018****Related U.S. Application Data**

(63) Continuation of application No. 29/525,379, filed on Apr. 29, 2015, now Pat. No. Des. 820,038.

(51) **LOC (12) Cl.** ..... **07-99**(52) **U.S. Cl.**USPC ..... **D7/392.1**; D9/449; D9/443; D7/396.2(58) **Field of Classification Search**

CLAIM

The ornamental design for a lid for a container, as shown and described.

DESCRIPTION

FIG. 1 is an upper perspective view of a lid for a container, illustrating the lid in a closed position and attached to an unclaimed container;

FIG. 2 is an upper perspective view of the lid for a container shown in FIG. 1;
FIG. 3 is a front view of the lid for a container shown in FIG. 1;
FIG. 4 is a back view of the lid for a container shown in FIG. 1;
FIG. 5 is a right side view of the lid for a container shown in FIG. 1;
FIG. 6 is a left side view of the lid for a container shown in FIG. 1;
FIG. 7 is a top view of the lid for a container shown in FIG. 1;
FIG. 8 is a bottom view of the lid for a container shown in FIG. 1;
FIG. 9 is an upper perspective view of the lid for a container shown in FIG. 1, illustrating the lid in an open position;
FIG. 10 is a front view of the lid for a container shown in FIG. 9;
FIG. 11 is a back view of the lid for a container shown in FIG. 9;
FIG. 12 is a right side view of the lid for a container shown in FIG. 9;
FIG. 13 is a left side view of the lid for a container shown in FIG. 9;
FIG. 14 is a top view of the lid for a container shown in FIG. 9; and,
FIG. 15 is a bottom view of the lid for a container shown in FIG. 9.
The broken lines showing a container in FIG. 1 depict environment and form no part of the claimed design. All other broken lines in the figures illustrate portions of the lid for a container that form no part of the claimed design.
